(57) CLAIM

The ornamental design for an ice skate, as shown and described.

DESCRIPTION

FIG. 1 is a front perspective view of an ice skate showing our new design;

FIG. 2 is a rear perspective view thereof; and,

FIG. 3 is a side view thereof.

The broken lines surrounding the shaded area on the skate upper and at the top portion of the skate blade form unclaimed boundaries of the design. The broken line showing of various features within the shaded area of the skate upper and of the remainder of the ice skate is for illustration purposes only and forms no part of the claimed design.
